United States Patent Office.

GEORGE THOMAS AND WILLIAM W. McLANAHAN, OF MILESBURG, PENNSYLVANIA.

Letters Patent No. 105,385, dated July 12, 1870.

IMPROVEMENT IN DOUBLE-TWEER FORGE-FIRES.

The Schedule referred to in these Letters Patent and making part of the same.

To all whom it may concern:

Be it known that we, GEORGE THOMAS and WILLIAM W. McLANAHAN, of Milesburg, in the county of Centre and State of Pennsylvania, have invented a new and valuable Improvement in the Double-tweer Forge-Fire; and we do hereby declare that the following is a full, clear, and exact description of the construction and operation of the same, reference being had to the annexed drawing, making a part of this specification, and to the letters and figures of reference marked thereon.

Figure 1 of the drawing is a vertical transverse section of our improved forge-fire.

Figure 2 is a vertical longitudinal central section of the same.

Our invention relates to an improvement in the double-tweer forge-fire, for refining purposes, and consists in bending the side-plates below the tweer-iron, thereby enabling the tweers to be laid stationary, and in such positions that they will not interfere with the manipulation of the loop for oxidation or other purposes.

The letter A of the drawing represents the oven or wall-plates of the fire.

In these walls are the semicircular openings b b, for the tweers c c, which are fixed in position.

Immediately below, and forming the support for the tweer, is the side plate B.

The letter e represents the bevel in this plate, at the upper part of the inside thereof, the proportion of the slope usually being one and a half inch base to three inches in height or depth. Thus, in a run of three inches, the plate is reduced from two and a half inches in thickness to one inch, usually.

g represents the bottom of the fire, which is made flat.

z z are the discharge-apertures for the cinders, one on each side, at about the same height, and are centrally placed, but lower down in the wall.

In the reduction and refining of iron, success depends, in a large measure, upon the proper oxidation and other chemical reactions produced by the mechanical agency of the workman at the forge-fire.

Great skill and care are required in the operation, and hence a forge-fire constructed in such a manner as to facilitate the manipulations, cannot fail to be of benefit.

In a single-tweer forge-fire, on account of the blast being, in a measure, spent before it reaches the opposite side of the loop, it is usually found that this, the fire-spirit side, is of inferior quality.

In the old double-tweer fires, with perpendicular sides, the tweer-irons had to be withdrawn whenever the loop was moved in the fire, thus involving machinery and time, besides much fuel in reheating the loop.

In our forge-fire the cross-blast promotes the equal reduction of the loop. No part of it, if properly manipulated, will be of inferior quality from want of blast.

To facilitate the manipulation, and allow the workman to raise, expose, or withdraw the loop, without hindrance, we give the tweer a stationary position sufficiently remote to be out of the way of the loop.

Thus, by means of the beveled side-plates, we are enabled to derive all the advantages arising from the use of the perpendicular walls in double-tweer forge-fires, without being obliged to remove the tweers every time the loop is raised. At the same time, the bevel of the plate presents no obstruction to the proper downward direction of the blast.

What we claim as our invention, and desire to secure by Letters Patent, is—

1. The improved double-tweer forge-fire herein described, having a level bottom, g, and the side plates B beveled at e, as and for the purposes specified.

2. the perpendicular side plate B, beveled at its upper and inner corner e, substantially in the manner and for the purposes specified.

In testimony that we claim the above, we have hereunto subscribed our names in the presence of two witnesses.

GEORGE ^{his} X THOMAS.
mark.
W. W. McLANAHAN.
